UNITED STATES PATENT OFFICE

108,353

DESIGN FOR A BOTTLE CAP

Serenus H. A. Young, St. Paul, Minn., assignor
to Young Engineering Laboratories, Inc.,
Minneapolis, Minn., a corporation of Minnesota

Application December 16, 1936, Serial No. 66,576

Term of patent 14 years

To all whom it may concern:

Be it known that I, Serenus H. A. Young, a citizen of the United States, residing at St. Paul, county of Ramsey and State of Minnesota, have invented a new, original, and ornamental Design for a Bottle Cap, of which the following is a specification, reference being had to the accompanying drawing forming part thereof.

Figure 1 is a plan view of a bottle cap, showing my new design.

Figure 2 is a side elevational view, showing my new design.

The characteristic features of my design reside in a cap of the configuration shown, provided

with a peripherally arranged shoulder and downwardly extending skirt portion, said skirt portion being composed of a plurality of successive substantially radially extending segments which are integral with and separated by triangular shaped plaits, and a V-shaped notch extending between the base of each plait and an adjacent side of a segment portion, thereby setting off the substantially parallelogram shape of the successive segments.

I claim:

The ornamental design for a bottle cap, as shown and described.

SERENUS H. A. YOUNG.
